UNITED STATES PATENT OFFICE.

WILLIAM E. CHAPMAN, OF NEW BRITAIN, CONNECTICUT.

TOOL FOR VACUUM-CLEANERS.

1,092,823.

Specification of Letters Patent. Patented Apr. 14, 1914.

Application filed September 4, 1913. Serial No. 788,176.

To all whom it may concern:

Be it known that I, WILLIAM E. CHAPMAN, a citizen of the United States, residing at New Britain, in the county of Hartford and State of Connecticut, have invented certain new and useful Improvements in Tools for Vacuum-Cleaners, of which the following is a specification.

My invention relates to improvements in tools for vacuum cleaners, and the object of my improvement is simplicity and economy in construction and convenience and efficiency in use.

In the accompanying drawing: Figure 1 is a front elevation of my improved tool for vacuum cleaners. Fig. 2 is a side elevation of the same. Fig. 3 is a bottom view of the same. Fig. 4 is a bottom view of the nozzle. Fig. 5 is a plan view of the mouth piece. Fig. 6 is a sectional view on an enlarged scale, on the line $z-z$ of Fig. 3. Fig. 7 is a similar view on the line $y-y$ of Fig. 2. Fig. 7^a is a similar view on the line $u-u$ of Fig. 7. Fig. 8 is a fragmentary view on the line $z-z$ of Fig. 6. Fig. 9 is a plan view on the same scale as Fig. 1 of the blank for the body of the mouth piece. Fig. 10 is a view of the blank, on an enlarged scale, for the end plate of the mouth piece. Figs. 11, 12 and 13 are views of the blank shown in Fig. 9 with certain portions bent to their final position. Fig. 14 is a front elevation, on the same scale as Fig. 1 of a modification of my tool. Fig. 15 is a fragmentary view of certain parts shown in Fig. 14, on the same scale as Fig. 6.

My improved tool for vacuum cleaners comprises a nozzle 10 and a mouth piece 14 separably connected thereto by means of screws 15. The nozzle 10 comprises a fan shaped body portion 9 having at the upper end a stem 11 and at the lower end a mouth 12. The mouth 12 has an elongated opening or slit 13 which is the lower terminus of the passage 20 through the nozzle. The lower surface 17 of the mouth 12 is finished off plane suitably for a bearing surface, inclosing the slit 13 on all four sides. Holes 16 extend vertically through the ends of the mouth 12. The mouth piece 14 comprises a short channel 18 that serves as an extension of the mouth 12 having a passage 19 that is of substantially the same cross-section as the slit 13 and is in registration therewith, and is provided with a pair of rollers 21, one on

each side of the slit 13 and pivotally mounted by their ends.

A method of construction for obtaining the features mentioned is as follows: The frame of the mouth piece 14 is made from a blank 23 as shown in Fig. 9, a pair of end plates 24 as shown in Fig. 10, and a pair of filler blocks 25. The blank 23 comprises a rectangular body at the middle and a pair of end pieces 27 at the ends thereof. The body 26 is of about the same length as the mouth 12 or slightly longer and has a central slot 28 that is of about the same dimensions as the opening 13 in the mouth 12, there being a small portion of the body material between the ends of the slot 28 and the ends of the body 26 in the form of flat bridges 29. The body 26 is bent at right angles along the lines 30 that are in line with the lateral edges of the slot 28 and which lines are the lateral border lines of the bridges 29. The portions of the body 26 outward from the slot 28 and the bridges 29 and connected to the said bridges 29 along the lines 30 consist of a pair of wings and these are each divided into two parts by being bent at right angles along lines 31 that are parallel to the slot 28 and in the reverse direction from the bends along the lines 30. Of these two parts, the inner parts 32 serve as the lateral walls of the channel 18, and the outer parts 33 form bearing wings having the upper surfaces suitable for engaging with the bottom bearing surface provided at the lower face 17 of the mouth 12. The end pieces 27 are each connected to the body 26 by a narrow piece of body material along the line 34 of about the width of the bridges 29, the material of which the blank is formed being slotted as shown at 35 outwardly from the said bridges 29. The said end pieces 27 are bent at right angles to the bridges 29 along the said lines 34 and in the same direction as the side walls 32 of the channel 18. The end pieces 27 comprise each an inner section 36 in the form of a rectangular plate connected by the middle to the body 26 along the line 34 and an outer section 37 extending outwardly from the middle of the outer edge thereof in axial alinement with the bridge 29 and of substantially the same shape and dimensions, and which fits in between the opposed faces of the lateral walls 32.

The blank 23 after the first bend men-

tioned is shown in Fig. 11 and after the second bend in Fig. 12, and in Fig. 13 the same is shown after all the bends mentioned have been completed and the blank 23 is in the final form. The bridge 29 and the end section 37 have holes 38 that are in registration one with the other and also with the hole 16 in the mouth 12 to receive the screw 15. The filler block 25 fills the space 10 at the end of the channel 18 between the bridge 29 and end section 37 and is in abutment with the inner section 36, and has a vertical hole 39 through which the screw 15 passes, and a horizontal hole 40 for the rivet 41. The rivet 41 also passes through holes 42 in the lateral walls 32 and secures the same to the filler block 25. The filler block 25 also has a threaded hole 42 extending inwardly from the outer end for 20 the screw 43 and which is in registration with holes 44, in the inner section 36, and 45 in the end plate 24. The screws 15 are provided on their upper ends with nuts 46 that engage with the upper surface of the 25 mouth 12. The end pieces 27 having bearing holes 47 for the ends of the rollers 21. Positioning pins 48 are provided in holes 49 on the end plates 24 and engage with 30 holes 50 in the end pieces 27 and serve to position these members relatively one to the other when held in engagement by the screw 43. The rollers 21 comprise each a shaft 35 51 and a cushion portion 52 exterior thereto. The shaft 51 is journaled in the bearing holes 47 between the inner faces of the end plates 24 so that when the said plates are in position in engagement with the end pieces 27 the shaft 51 is positively held in operative 40 position in the bearings. The cushion portion 52 is made slightly shorter than the space between the bearings 47 so that when the end plate 24 is removed from either end the roller 21 can be slipped along longitudinally sufficiently to permit one end to 45 be freed from its bearing 47, when the said end of the roller 21 can be brought outwardly and then the roller removed from the frame.

In the modification shown in Figs. 14 and 50 15 the mouth 12^a is extended integrally and the rollers 21 are positioned alongside the same. The rollers 21 are positioned relatively to channel 18 so that the lower end of the latter will be close to the floor and 55 the rollers 21 are also positioned relatively to the adjacent edges 53 of the frame so as to slightly overhang the same, as will be noted in Fig. 6. The rollers therefore

serve as a cushioning device to prevent damage to the mop-boards or side walls of the 60 room when the tool is brought into contact therewith. At the same time the said rollers serve to reduce the frictional resistance to moving the tool over the floor.

As has been mentioned, and as shown in 65 Fig. 6, the lower end of the channel or the inlet passage is close to the floor. In other words, with the rollers in contact with the floor the said lower end of the suction inlet is slightly elevated relatively to the floor. 70 As the rollers are positioned alongside the passage one on each side, and adjacent the same it follows that the entire floor between the rollers is apparently subject to the effect of the suction or vacuum effect in the 75 passage or inlet. This is practically the case when used over a bare floor. When however it comes to the case of operation on a carpet or rug, then the effect mentioned is modified after the following manner. In 80 such case the effect is that the portion of the carpet between the rollers is flexed and lifted until the middle part thereof is brought into contact with the said lower end of the passage. Then, as the nozzle is 85 moved along, successively the different parts of the carpet are brought into operative relation to the passage, and in a most effective manner.

I claim as my invention:—

1. A tool for vacuum cleaners comprising 90 a nozzle body having an inlet, and a pair of rollers journaled in bearings on the said nozzle body, and positioned alongside and one on each side of the said inlet, and the 95 lower end of the inclosing wall of the said inlet being plane and positioned slightly elevated relatively to the plane of the lower edges of the said rollers.

2. A tool for vacuum cleaners comprising 100 a nozzle body having an inlet, the walls of the said inlet extending close to the floor, and a pair of rollers journaled in bearings on the said nozzle body, and positioned alongside the said inlet and separated therefrom by the said walls, the exterior of the said rollers being of cushioning material, and the said rollers being so positioned relatively to the said nozzle body that the outer edges project beyond the outer edges of the 110 said nozzle body.

WILLIAM E. CHAPMAN.
